UNITED STATES PATENT OFFICE.

LE ROY S. WHITE, OF WATERBURY, CONNECTICUT.

ELECTRIC CALL AND SIGNAL.

SPECIFICATION forming part of Letters Patent No. 284,348, dated September 4, 1883.
Application filed July 23, 1883. (No model.)

To all whom it may concern:

Be it known that I, LE ROY S. WHITE, of Waterbury, in the county of New Haven and State of Connecticut, have invented a new and useful Improvement in Electric Calls and Signals, of which the following is a specification.

My invention is more particularly applicable to calls or signals which are intended for use on telephone-lines for calling any one of a number of subscribers on the same line without calling or disturbing any of the other subscribers, and the call or signal instrument which forms the subject of the present invention is in some respects similar to that which forms the subject for Letters Patent No. 239,207, granted to me March 22, 1881. According to both my former and my present invention the instruments of the several subscribers and at the central office are furnished with ratchet or toothed barrels having an equal number of teeth, which must be more than the number of subscribers on the line, and each of which has a projection, and the barrels of all the instruments are brought to a common starting-point by the armatures of electro-magnets, through which a succession of impulses are sent, the barrels all being arrested at the starting-point by stops, which are obtruded in the way of the projections on the barrels. Before any of the subscribers can be called the ratchet barrels of all the instruments must be released from their stops and again advanced. According to my former invention two batteries of unequal strength were necessary, and the weaker battery was used to advance the ratchet barrels of the several instruments step by step, while a current from the stronger battery was necessary to release the ratchet barrels from their stops and to send a call-current.

The object of my present invention is to enable one battery or single-current magneto-machine only, which need not be of any particular strength, to serve all the purposes of advancing the ratchet barrels step by step, of releasing the barrels, and of sending call-currents, and thereby to simplify the call or signal system, and to render unnecessary any careful attention to the strength of the battery. To this end I employ, in connection with the ratchet-barrel, electro-magnet, armature, and

actuating-pawls of a call or signal instrument of the kind above described a permanent magnet carrying a stop, and a double key for sending currents of opposite polarities. By 55 operating one key I send currents of such polarity that the permanent magnet will be moved in one direction, and so caused to move the stop into the path of the projection on the ratchet-barrel, and that the ratchet-barrel 60 will be advanced until said projection is arrested by said stop, and by operating the other key I send currents of opposite polarity, which cause the permanent magnet to move in the opposite direction to withdraw the stop to release the barrel. Each instrument is also provided with a bell-magnet and vibrating bell, and with a circuit-closer for shunting a part of the current through the bell-magnet, and the stop carried by the aforesaid permanent 70 magnet, when moved into position to arrest the ratchet-barrels, also prevents the movement of the barrel-operating armature far enough to operate the said circuit-closer.

In the accompanying drawings, Figure 1 is 75 a partly sectional elevation of an instrument embodying my invention. Figs. 2 and 3 are plans of the instrument and operating-key connected by circuit-wires. Fig. 4 is a detail view of the ratchet-barrel and its actuating-pawls. Fig. 5 is a perspective view of the barrel alone, and Fig. 6 is a plan of the permanent magnet and the stop.

Similar letters of reference designate corresponding parts in all the figures. 85

A, B designate, respectively, the call and bell electro-magnets, which are mounted on the base C; and A', B' designate, respectively, the call-armature and bell-armature, the latter of which carries a bell-hammer, B'. Upon the 90 standard B³ is mounted the bell B⁴, and the hammer B', under the control of the springs a, is operated by the bell-magnet like the hammer of any ordinary vibrating bell.

D designates the barrel, mounted in bearings, 95 so that it is capable of free rotation, and having teeth b around its circumference adjacent to one end, and a single notch, c, in its circumference adjacent to the other end. As here shown the said notch is simply a continuation of one of the notches which form the teeth b; but it may be considered as a notch

independent of said teeth. The barrel D is also furnished with a long tooth or projection, *d*, which is out of line with the teeth *b*.

Upon the call-armature A' are secured two pawls, *e e'*, which act at opposite points in the circumference of the barrel, and the former of which, *e*, acts during the attractive movement of the armature to advance the barrel a half-tooth, while the latter, *e'*, acts during the retractive movement of the armature to advance the barrel the other half of a tooth. These two pawls act upon the barrel in a manner somewhat resembling the reverse movement of an escapement, preventing the ratchet-barrel 15 from being advanced too far, and giving it an exactly equal and uniform movement at each movement of the call-armature A'.

To the call-armature A' is secured a tooth, *f*, which is in range with the notch *c* in the barrel, 20 and when the armature is attracted and the notch *c* is opposite the tooth *f* the latter will enter said notch and permit a full movement of the armature; but when the tooth *f* strikes upon the cylindric surface of the barrel so 25 great an attractive movement of the armature will be prevented.

Upon the top bar or plate, C', of the magnets is a lug or bracket, *g*, in which is a contact-screw, *g'*, (best shown in Fig. 1;) and E designates a spring, which is normally out of contact with said screw, but which is capable of being moved to make contact therewith. The said screw and spring constitute a bell-circuit closer for the bell-magnet B, and the spring is 30 connected by a rod or pin, *g''*, with an insulated projection, *g'''*, on the call-armature A', so as to be actuated thereby. When the notch *c* in the barrel D is opposite the tooth *f*, the armature A' will move sufficiently far to close the 35 circuit through E *g'*; but otherwise it will not be allowed a great enough movement to close said circuit.

F designates a permanent magnet, here shown as pivoted at *h* to the bar C', and the 40 ends of which embrace or straddle the pole *h'* of the call-magnet A. To the ends of the magnet F is attached a plate, F', having portions *i i'* of different degrees of projection. The poles of this permanent magnet are designated 45 by the letters *n s*, and when a current of such polarity is sent through the call-magnet A as to attract the pole *n* the permanent magnet is moved into the position shown in Fig. 2. The portion *i* of the stop-plate F' is then out of line 50 with the projection *d* on the barrel, and does not arrest the latter; but when the polarity of the current is reversed the pole *s* is attracted and the permanent magnet is moved to bring the portion *i* of the stop-plate F' into line with 55 the projection *d*, so that when the latter strikes it the barrel D will be arrested. At the same time that the stop-plate F' is moved so that the portion *i* will arrest the barrel the portion *i'* will be brought into line with the pawl *e'* and 60 will prevent the full movement of the armature and the closing of the circuit through E 65

g' even if the notch *c* be opposite the tooth *f*. The purpose of this will be hereinafter referred to.

G G' designate the circuit-wires, which are 70 connected with binding-posts *j j'*, and the said binding-posts are in a closed circuit, which includes the call-magnet A. The said binding-posts are also connected by an open circuit, which includes the spring E, the contact *g'*, 75 and the bell-magnet B. Of course, when circuit is closed through the spring E, contact *g'*, and bell-magnet B, a portion of the current will be shunted through the bell-magnet and the bell sounded. 80

H designates a double key provided with two buttons, N S, for sending currents of opposite polarity, and which is connected by conductors I I' with a single battery, I², or with a single-current magneto-electric machine. The strength of the battery may be 85 variable.

I would here remark that the notches *c* in the barrels of the several instruments on the line must be formed at different distances behind the long tooth or projection, *d*, corresponding to the different numbers of the several subscribers. 90

I will now describe the operation of calling any one of the subscribers. 95

In the first place I operate the key S a greater number of times than there are teeth in the barrel D. The first current sent will attract the pole *s* of the permanent magnets F, and will move the stop-plates F', so that the portions *i* will be in line with the projections *d* of the several barrels D, and the succeeding currents will bring all the barrels to a state of rest with their projections *d* stopped by the portions *i*, that being the common starting-point. Before each barrel reaches the point at which it is arrested the notch *c* passes the tooth *f*, and if it were not prevented the circuit-closer E *g'* would momentarily sound the bell. This is prevented by the portion *i'* of the plate F', carried by the permanent magnet, being in line with the pawl *e'*, and forming an abutment therefor to prevent the tooth *f* from entering the notch *c* when the stop F' is 105 adjusted to arrest the barrel; but when the barrel is released the portion *i'* is moved away from the pawl *e'*, and no longer arrests the movement of the armature. The key N is then operated, which sends a current of reverse polarity, and the permanent magnet F is 110 moved to carry the stop F' away from the tooth or projection *d*, thus releasing the barrels of all the instruments. To call any of the instruments I now operate the key S a number of times—one less than the number of the 115 instrument or subscriber to be called—and then operate the key N once, which serves to bring the notch *c* in the barrel D of the instrument to be called opposite the tooth *f*, and to move the tooth into the notch, and so allow 120 the armature to close the circuit through E *g'* and the bell-magnet B. For example, to call 125

the armature to close the circuit through E *g'* and the bell-magnet B. For example, to call 130

subscriber No. 1, I would simply press the key N once; to call subscriber No. 2, I would press the key S once and the key N once; to call subscriber No. 3, I would press the key S twice 5 and the key N once, and to call subscriber No. 4, I would press the key S three times and the key N once. In calling any instrument after No. 1 it is necessary to press the key S and then the key N, because as long as the key S is pressed the portion i' of the stop F' is held 10 in line with the pawl e' , and hence the calling of any instrument before the one desired will be prevented. When the tooth or projection d is brought round to the stop-plate F', it presses 15 upon the said plate only when the pawls e e' are acting to move it forward, and when the armature is at rest the tooth or projection is very slightly out of contact with said stop-plate. When a current is sent to release the bar- 20 rel, the permanent magnet, being very light, is moved before the armature A', and hence is moved to withdraw the stop-plate from in front of the projection d before the latter im- pinges against said plate.

25 What I claim as my invention, and desire to secure by Letters Patent, is—

1. The combination, with the electro-magnet, the toothed barrel provided with a notch, the armature provided with a turning pawl or 30 pawls for advancing the barrel, and with a tooth for entering said notch, and a bell-cir-

cuit closer capable of operation by said armature, of a permanent magnet capable of operation by the electro-magnet and carrying a stop for arresting the barrel at a predetermined 35 point, substantially as and for the purpose described.

2. The combination, with the electro-magnet, the toothed barrel provided with a notch, the armature provided with a turning pawl or 40 pawls for advancing the barrel, and with a tooth for entering said notch, and a circuit-closer for a bell-circuit capable of operation by said armature, of a permanent magnet capable of operation by the electro-magnet, and 45 carrying a stop to arrest the armature and prevent a sufficient movement thereof to allow the armature to close the said circuit, substantially as and for the purpose described.

3. The combination of the electro-magnet A, 50 the toothed barrel D, with a projection, d , and notch e , the armature provided with pawls e e' , a bell-circuit closer, the permanent magnet F, and the stop-plate F', carried by said magnet, and serving both as a stop to the said 55 barrel and the said armature, substantially as and for the purpose described.
